COMBINED SPICE HOLDERS AND WALLED MOUNTED RACK

Daniel A. Ferrara, Jr., New Milford, Conn., and Barry P. Benedek, New York, N.Y., assignors to Ferrara Benedek Design, Inc., New York, N.Y.

Filed Jan. 8, 1975, Ser. No. 539,467

Term of patent 14 years

Int. Cl. D7—06

U.S. Cl. D7—52

FIG. 2

FIG. 1

FIG. 3

FIG. 4

FIG. 1 is a left side elevational view of combined spice holders and wall mounted rack embodying our novel design;

FIG. 2 is a front elevational view thereof;

FIG. 3 is a bottom plan view thereof; and

FIG. 4 is a rear elevational view thereof.

We claim:

The ornamental design for combined spice holders and wall mounted rack, as shown.
